UNITED STATES PATENT OFFICE.

JOHN BROOKS, OF PLAINFIELD, NEW JERSEY.

STEREOTYPE-CASTING MACHINE.

SPECIFICATION forming part of Letters Patent No. 351,040, dated October 19, 1886.

Application filed August 7, 1885. Serial No. 173,844. (No model.)

To all whom it may concern:

Be it known that I, JOHN BROOKS, of Plainfield, in the county of Union and State of New Jersey, have invented a new and useful Improvement in Stereotype-Casting Machines, and the following is declared to be a description of the same.

In preparing stereotype-plates for printing it is usual to cast the type-metal in a mold, the printing or type surface being produced by a paper matrix, and casting-boxes have been made, wherein the core-block has been hinged to the casting-box and the parts adjusted and operated by hand assisted with ordinary mechanical lifting appliances.

The object of my invention is to form a casting-box that shall be easily and quickly opened and closed, and that shall move parallel, or nearly so, when the parts are acted upon, and thereby separate the concave side of the stereotype-plate from the core-block.

My improved casting-machine is made with suitable framing for supporting the core-block and with a movable casting-box. The core-block is nearly vertical and stationary, and the casting-box is upon trunnions connected by standard-moving carriages having slide-ways upon the frame. The carriages are moved back and forth by links and crank-pins to disks upon a shaft that is operated by a lever and pawls and a ratchet-wheel upon the shaft. The casting-box is provided with side bars to hold the paper matrix, and it is held by a catch and drawn forward in an almost perpendicular position into contact with the semi-cylindrical core-block, there being the necessary space for receiving the melted metal that is cast to form the stereotype-plate, and when said plate is to be removed the casting-box is forced back away from the core-block, carrying with it the stereotype, and it is then tipped into a horizontal position and supported by a rest, while the stereotype is being removed or the matrix secured in position.

In the drawings, Figure 1 is an elevation of my improved casting-machine in position for casting the stereotype-plate. Fig. 2 is a partial elevation, the casting-box being horizontal and in section. Fig. 3 is a plan view of the machine, as shown in Fig. 2. Fig. 4 is a

cross-section at $x x$ of the core-block and casting-box, and Figs. 5 and 6 are an elevation and plan view of a device for cutting and truing the edge of the stereotype-plate. Fig. 7 is a section through the sliding cutter-plate at 55 the top of the core-block; and Fig. 8 is a perspective view of the hub, rest, and catch, and Fig. 9 is a partial section of the end plate or gage and casting-box.

A and A' are the side frames of the machine, 60 and A'' is one end frame, and upon the upper edges of said side frames are the slide-ways I. The end frame, B, is preferably slightly inclined and bolted to the side frames, and the bracket-frame B' is preferably formed in one with the 65 end frame, B, and upon said bracket-frame there are journal-boxes C for the operating-shaft i. The core-block D is bolted to the end frame, B, and it is formed as a long block of metal, semicircular in section, and having 70 grooves in its circular face, and these grooves receive the cast metal and form the ribs upon the inner surface of the cast stereotype-plate. There are disks h h' upon the shaft i outside the journal-boxes C, and there are ratchet-wheels l l' keyed upon the shaft i, and a lever, n', having an eye, n, loose, upon the shaft i, between the ratchet-wheels, and there are pawls m m' upon said lever n' to engage the teeth of the ratchets l l' in opposite directions, 75 as shown by dotted lines in Figs. 1 and 2, so that the shaft i can be turned by the lever n' in one direction by the pawl m and ratchet l, and in the other direction by the pawl m' and ratchet l'. It is to be understood that when 80 both the pawls m m' are in contact with their respective ratchet-wheels the lever is connected and the shaft i will be rotated either way with the lever n'; but if the space is limited the lever can be reciprocated if one pawl is thrown 85 out of action. There are links k k' connected by crank-pins to the disks h h' and by pivots to the standards F of the sliding carriages F, so that said links move the carriages and casting-box E back and forth upon the slide-ways 90 I. As the shaft i receives half-rotations, the stop-pins 10 act to limit the movement in one direction. The casting-box E is preferably 95 made with strengthening-ribs 4, and is semi-circular in section, larger than the core-block 100

D, and upon the inner surface of the casting-box there are side bars, $a a'$, undercut on their lower edges, and held to the casting-box by pins 1. There is an end gage or semi-cylindrical plate, b , having a beveled edge in the lower part of the casting-box, and said plate is recessed as shown in Fig. 2, and it is adjustable and is provided with bolts at 2 that pass through holes in the casting-box, and secure the same, and which holes allow such plate to be shifted and to be placed in the proper position.

In the upper end of the casting-box there is an end gage or semi-cylindrical recessed plate, c , also having a beveled edge to which the lipped bars and handles 3 are connected, and the casting-box E is pivotally mounted by its trunnions F' in bearings upon the standards F^2 of the carriages F, and the casting-box can be tipped up nearly perpendicular or placed horizontal, the handle 5 being provided for that purpose.

d is the paper matrix, its top and bottom ends being shown as under the edges of the end plates or gages, b and c , in Fig. 2 and its other two edges being shown under the edges of the side bars in Fig. 4, said plates and side bars holding the matrix to place and determining the size of the stereotype-plate, and against which its edges are cast. In cases where the gage or end plate c is not used I employ a sheet-metal plate that covers the upper edge of the paper matrix and is received under the edges of the side bars, $a a'$.

Upon the sliding carriages F there are standards e , and a shaft, e' , passes from one standard to the other, and outside one standard is a handle, f , and upon said shaft, between the standards e , is a hub, g , carrying the rest g' and the catch g^2 , the rest g' supporting the heavier end of the casting-box in the position shown in Fig. 2, and the catch g^2 entering a slot in the plate 6 and catching on the back of said plate and retaining the same and the casting-box to which it is attached in the position shown in Fig. 1 during the forward and backward movement. There is a bolt, 7, in the base of one standard e , and said bolt is adjustable to form a rest for the handle f and to adjust the catch g^2 in its relation to the slotted plate 6.

The operation of the parts is as follows: Starting with the position shown in Fig. 2, the side bars a and plate c being removed, the paper matrix is placed within the casting-box E, its lower edge being placed underneath the edge of the plate b , the plate c and bars $a a'$ are then put in place and cover the other edges of the paper matrix. The attendant then grasps the handle 5 and lifts the casting-box into an almost perpendicular position, at which time the catch g^2 enters the slot in the plate 6 and catches, locking and holding the casting-box in its upright position. The attendant then grasps the lever n' , Fig. 2, and swinging it outward and downward, the pawl m engaging

the teeth of ratchet-wheel l and revolving the shaft i and disks $h h'$ in the direction of the arrow, Fig. 2, and by the links $k k'$ drawing the sliding carriages F and casting-box E into the position shown in Fig. 1, wherein the core-block D is within the casting-box, and the parts are tight and secure for casting. This position is also shown by the section, Fig. 4, the relative position of the casting-box to the core-block 75 being accurately determined by the bar o and adjusting-screws o' , that form stops for the casting-box. The molten metal for forming the stereotype-plate is poured over the top of the core-block D, upon top of which I 80 prefer to secure a slanting guide-block, N, Fig. 5, to direct the flowing metal. After casting the metal it is preferable to separate the surplus metal in the gate from the upper end of the stereotype-plate and a cutting 85 device for accomplishing this work I have shown in Figs. 5 and 6. If desired, the end plate or gage c might have two or more pouring-channels (shown in Fig. 9 by dotted lines at c^2 , Fig. 3) cut into its face, and it 90 might come tight up against the core-block, in which case the metal filling the pouring-channels would only have to be broken off. After casting the plate, and when it is sufficiently cooled, the attendant grasps the handle n' , Fig. 1, and raises it, the pawl m' engaging the teeth of ratchet-wheel l' , and revolving the shaft i and disks $h h'$ and moving the links $k k'$ and sliding carriages F back into the position of Fig. 2, carrying the casting-box 95 and stereotype away from the core-block D. The attendant takes the handle 5 in one hand and the handle f in the other hand and raises the handle f , depressing the catch g^2 , releasing the casting-box from said catch, and then 100 by handle 5 tipping said casting-box into a horizontal position, resting upon the rest g' . The side bars a and plate c are now removed, and the stereotype-plate and paper matrix 105 lifted out. The paper matrix is now peeled away from the plate and may be placed in the casting-box, as heretofore described, and the operations repeated to form a second plate, if desired.

Figs. 5 and 6 represent a device for cutting 115 and trimming the end of the cast stereotype-plate that is uppermost in the box, and for separating from it the superfluous metal in the gate above while said metal is soft and hot. A metal L-shaped head-piece, N, is adapted 120 to setting upon top of the core-block D and to be bolted to the same, and it has an inclined curved face, at r , acting as a funnel, down which the melted metal is poured in casting, and a face-plate, r' , resting against 125 and bolted to the core-block D. There is a sliding plate, s , having a circular beveled cutting-edge, s' , between the core-block D and the head-piece N, and said plate is slotted for the bolt t , and it is operated by the links t' , 130 connected to the bolt t , and pin v in the lugs r^2 of the frame-plate r , and said pin v has con-

5 nected to its lower end the operating-lever *u*, the movement of which lever works the sliding cutter-plate *s* to force said cutter through the soft and hot metal and cut and separate the surplus metal or gate from the stereotype-plate to finish the edge of the said stereotype-plate.

10 I do not limit myself to the precise mechanism for operating said cutter as heretofore described, as the same might be operated by different devices.

I claim as my invention—

15 1. The combination, with the core-block *D*, of the casting-box *E*, and mechanism, substantially as specified, for supporting the same, the side bars, *a a'*, provided with pins 1, entering holes in the casting-box, the end plate *b* and its bolts 2, the end plate *c* and handles 3, the bars *a a'* and plates *b c* being undercut to receive the edges of the paper matrix, substantially as specified.

20 2. The core-block *D* and casting-box *E*, mounted upon trunnions, and their bearings and the sliding carriage *F*, in combination with a handle, 5, forswinging the casting-box, a rest, *g'*, a catch, *g''*, and a slotted plate, 6, to lock the casting-box in an upright position, and a handle, *f*, by which said catch *g''* is operated, substantially as specified.

25 3. The core-block *D* and casting-box *E*, in combination with the sliding carriages *F*, trunnions *F'* and their bearings, standards *F''*, standards *e*, shaft *e'*, handles *f*, hub *g*, rest *g'*, catch *g''*, and the slotted plate 6, and handle 5, substantially as specified.

30 4. The core-block *D* and the stationary frame to which it is connected, and the casting-box *E*, having trunnions, in combination with the sliding carriages having bearings for the trunnions, and the disks *h h'*, shaft *i*, links *k k'*, ratchet-wheels *l l'*, pawls *m m'*, hub *n*, and lever *n'*, substantially as specified.

35 5. The combination, in a stereotype-plate

45 casting-machine, of a core-block bolted to the frame of the machine and maintained in an almost perpendicular position, a casting-box 50 adapted to receive the paper matrix, and provided with trunnions at the sides thereof, and sliding bearings for the same and adapted to being turned up almost perpendicularly and placed against the core-block for casting and to being turned down horizontally for the removal of the stereotype-plate, substantially as specified.

55 6. The core-block *D* and casting-box *E*, and the trunnions, bearings, and sliding carriages for the same, in combination with the disks *h h'*, shaft *i*, and links *k k'*, and a lever by which the said parts are operated, substantially as specified.

60 7. The casting-box *E* and core-block *D*, in combination with the head-piece *N*, the sliding cutter-plate *s*, the bolt *t*, link *t'*, the pin *v*, and lever *u* for separating the surplus metal from the edge of the stereotype-plate, substantially as specified.

65 8. The combination, with the casting-box *E*, the side bars, *a a'*, and end plates for holding the matrix, of the core-block *D*, the bar *o*, and adjusting-screws *o'*, substantially as set forth.

70 9. The combination, in a stereotype-casting machine, with the core-block, casting-box, and gage for the end of the stereotype-plate, of a head-piece upon the core-block, a cutter for 75 removing the surplus metal from the edge of the stereotype-plate, and mechanism, substantially as specified, for giving motion to the cutter, substantially as set forth.

Signed by me this 1st day of August, A. D. 80
1885.

JOHN BROOKS.
